UNITED STATES PATENT OFFICE.

RICHARD FLEMING AND CROMWELL A. B. HALVORSON, JR., OF LYNN; MASSACHUSETTS,
ASSIGNORS TO GENERAL ELECTRIC COMPANY, A CORPORATION OF NEW YORK.

ARC-LAMP.

No. 926,732.

Specification of Letters Patent.

Patented July 6, 1909.

Application filed November 16, 1903. Serial No. 181,382.

To all whom it may concern:

Be it known that we, RICHARD FLEMING, and CROMWELL A. B. HALVORSON, Jr., citizens of the United States, residing at Lynn, county of Essex, State of Massachusetts, have invented certain new and useful Improvements in Arc-Lamps, of which the following is a specification.

The object of our present invention is the improvement of arc lamps.

More particularly our invention relates to arc lamps in which the major portion of the illumination from the lamp is given by a flaming or luminous arc, as distinguished from those in which practically all of the illumination comes from electrodes heated to incandescence. With these lamps the products of combustion from the arc are not all permanent gases, as is substantially the case where carbon electrodes are employed, but contain matter which condenses to solid form upon contact with suitable condensing surfaces. This necessitates a lamp arranged so that the solid matter cannot be deposited where it will clog up or otherwise hurt the operation of the lamp. As the incandescence of the electrodes is not relied upon to furnish the major portion of the illumination of the lamp, it is often found desirable to form one of the electrodes out of good conducting material so proportioned and arranged that it will not be consumed by the heat of the arc, and our invention also comprises a novel construction and arrangement of this electrode.

The many novel features which characterize our invention will be pointed out with particularity in the claims annexed to and forming a part of this specification.

For a better understanding of our invention reference may be had to the accompanying drawings in which we have illustrated an embodiment of our invention.

Of the drawings, Figure 1 is a perspective view of an arc lamp with the casing and globe in section to disclose the mechanism of the lamp; Fig. 2 is another perspective view of the lamp viewed from a different position with the case and globe removed; Fig. 3 is a sectional elevation showing the lamp mechanism; Fig. 4 is a diagram illustrating the circuits of the lamp; and Fig. 5 is a partial sectional elevation and Fig. 6 is a perspective view illustrating an auxiliary electrode scraping mechanism.

Referring to the drawing, 1 represents a lamp cap or top on the upper side of which suitable means are provided by which the lamp may be suspended. From the under side of the cap or top 1 an integrally formed 60 tubular boss 2 depends. This boss is threaded interiorly to receive the threaded upper end of a short metal tube 3, as is clearly shown in Figs. 1, 2 and 3 of the drawings. The boss 2 has a series of apertures 4 formed in it. The lower end of the tube 3 is also threaded to engage the upper end of the interiorly threaded cylinder 5 extending through and integrally connected to a circular member 6. The upper end of a 70 section of metal tube 8 is threaded into the lower end of the cylinder 5. The section 8, which is similar to section 3, except that it is considerably longer, is also threaded at its lower ends to engage an interiorly threaded tubular boss 9, projecting upward from the disk-shaped platform 10. The section 8 is surrounded by a layer 11 of material which is an insulator both of heat and electricity.

A tube section 12 of metal is secured to 80 the under side of platform 10, and extends in line and in open communication with the sections 3 and 8. In the construction which we have shown in the drawings, the upper end of the section 12 is provided with a 85 flange 13, which abuts against a metallic washer 14, secured to the platform 10 by a pair of screws 15. The screws 15 are insulated from the platform 10 in any suitable manner, and a layer 16 of the insulating 90 material is interposed between the washer 14 and the under side of the platform 10. Clamping nuts 17 on the ends of the screws 15 are employed for holding the flange 13 against the washer 14 and to the platform 95 10. Preferably open ended slots 18 are formed in the flange 13 through which the screws pass. This facilitates a ready removal of the tube 12 from the platform 10 whenever it becomes desirable. With the 100 construction employed, it will be seen that the section 12 is secured to the platform 10 while it is at the same time insulated therefrom. Slots or grooves 19 and 20 are formed at opposite ends of the lower end of the section 12. A somewhat massive arc-shaped piece 21 of thermally and electrically conducting material, such as copper, having a considerable heat-dissipating capacity, passes 105 through these slots and forms the non-con- 110

suming positive electrode of the lamp. The arc on which this piece of metal 21 is formed is practically 180 degrees. A pair of bowed pieces or members 22, pivoted at their mid-
 5 dle points to opposite sides of the tube sec-
 tion 12, have the ends of the arc-shaped electrode 21 clamped between their ends. In the construction shown the electrode is
 10 pivoted at or near the center from which its arc is formed.

A lug 23 projects from the upper side of one of the pieces 22. A link 24 connects the lug 23 with a bar 25 which passes trans-
 15 versely through an opening formed for the purpose in platform 10, being insulated there-
 from by a suitable bushing, or in any other manner. The upper end of the bar 25 is connected to, but insulated from, the lower end of a U-shaped armature 26. The legs
 20 of the U-shaped armature 26 pass axially into one each of a pair of tubular magnet coils 28. These magnet coils, which may be of ordinary construction, have lugs 29 projecting from their end pieces 30. Suitable
 25 screws passing through these lugs secure the magnet coils to the tube section 8. One member 31 of a dash pot 31' is secured to the under side of the armature 26. The other member 32 of the dash pot is secured
 30 to the platform 10. The two members of the dash pot are arranged to prevent a rapid downward movement of the armature 26, without hindering the upward movement of the lamp.

35 A bracket 33 is secured to, but insulated from, the upper end of the tube section. A rod 34 extends from the under side of the bracket 33 toward the platform 10. The lower end of the rod 34 is directly connected
 40 to a washer or plate 35 which is secured to, but insulated from, the platform 10, by a similar plate 36 of insulating material. A rod 37 also extends down from the bracket 33 parallel to the rod 34. The rod 37, which
 45 may be secured to the bracket in a suitable manner, as by a threaded connection, passes downward through apertures formed for the purpose in platform 10, and plates 35 and 36. A tube 38 surrounds the major portion
 50 of the rod 37 which forms a guide upon which the tube may be moved longitudinally. An arm 39 extending at right angles from the lower end of the tube 38 carries at its outer end a socket in which the consum-
 55 ing negative electrode 40 is held in line with the axis of the tube sections 3, 8 and 12. The electrode preferably is formed out of, or contains, some material such as the magnetic oxide of iron, titanium carbide, or other
 60 material giving a flaming or luminous arc.

An arm 41 is clamped to the upper end of the tube 38. The outer end of the arm 41 is bifurcated and the bifurcations straddle the rod 34. The arm 41 forms a means for pre-
 65 venting rotation of the tube 38 and conse-

quent angular displacement of the electrode 40 about said tube.

A clutch 45 of ordinary construction connects the armature 26 and the tube 38. The tubular yoke 46 of the clutch 45 surrounds the tube 38, and the pawl 47 of the clutch is pivoted thereto. One end of the pawl is provided with an aperture through which the shank 31" of the dash pot member 31 passes. The other end of the pawl is adapted to firmly engage and lift the tube 38 in the ordinary manner when the armature 26 is raised. A second clutch 49 comprises a yoke 50, which surrounds the tube 38 and a pawl 51 pivoted to the yoke. The inner end of this pawl is adapted to engage the tube 38 whenever the outer end of the pawl is elevated. One end of a long helical spring 52 is secured to the outer end of the pawl 51. The other end of the spring 52 is secured to a lug, which depends from the bracket 33. The spring 52 normally holds the pawl 51 in such position that its inner end engages the tube 38. The pawl 51 is preferably formed with an aperture through which the rod 34 passes. This prevents angular displacement of the clutch.

A member 53 is adjustably secured to the rod 34. This member is provided with a bifurcated extension 54 which straddles the tube 38. The upper surface of the extension 54 forms a stop, against which the yoke 46 of the clutch 45 rests when the armature 26 is at the lower limit of its movement. The member 53 is provided at its under side with a lug 55 which forms a stop against which the outer end of the pawl 51 impinges when the tube 38 is given a sufficient upward movement. This impingement causes the clutch to release the tube 38. An adjustable collar 56 is mounted upon the rod 34 against the upper side of which the outer end of the pawl 51 normally rests.

A tube 57 surrounds the tube 38. The upper end of the tube 57 is provided with an out-turned flange 59 which prevents the tube from dropping through the washer 35, and the platform 10. The tube 57 is arranged to telescope or slide on the tube 38. The tube 57 may be forced upward against the underside of the yoke 50 to cause the clutch 49 to release the tube 38 whenever it may be desirable, as in trimming the lamp.

A vertical magnet coil 60 is mounted on the upper side of the platform 10. The armature 61 for the magnet coil is carried by one end of an arm 62 pivoted intermediate its ends in lugs 63 projecting upwardly from an extension to the end piece 64 of the magnet. A terminal or contact member, such as a carbon block or rod 65, is carried by the outer end of the extension 62, and a similar terminal 66 is carried by the extension 64. When the coil 60 is not energized the electrodes 65 and 66 engage under the action of

a spring 62', see Fig. 3. When the coil 60 is energized, and the armature 62 is attracted the contacts 65 and 66 separate. The clamps which hold the contact members 65 and 66 are insulated from the extension and arm in any suitable manner, as indicated at 67 and 68 respectively. A resistance spool 69 is also mounted on the upper side of the platform 10. A coil 70 having its axis horizontal is carried at the upper end of the tube section 8 by brackets 71 connected to opposite sides of the tube section. One end of a coöperating armature 72 is pivoted to the end piece 73 of the magnet. The other end of the armature carries an insulated contact 75, which coöperates with a contact 76 carried by, and insulated from, the other end piece 74 of the magnet 70. When the magnet coil 70 is excited by the proper current the armature 20 will be attracted and the contacts will engage for a purpose to be hereinafter described.

A casing 77, which may be formed out of sheet metal, surrounds the lamp mechanism located between the member 6 and platform 10. This casing is carried from the member 6 in any suitable manner, as by means of screws 78, which pass transversely through a down-turned flange 6' formed on the member 6. The lower end of the casing closely surrounds the platform 10. For the purpose of ventilating the lamp mechanism a series of perforations or apertures 79 may be formed in a belt around the lower end of the casing 77. A suitable annular hood 80 is carried by the lower end of the casing so as to prevent dust or water from entering the casing through these apertures. Another annular hood or member 81 is carried by the casing 77 below the hood 80. Suitable screws 82 passing transversely through the annular member 81 serve as a means for securing a transparent or translucent globe 83 in place. The globe 83 may be formed with an opening at the bottom normally closed by a member 84 detachably secured to the globe for that purpose. In order to secure a proper amount of ventilation in the globe 83 an opening 85 may be formed in member 84. In addition to the opening 84, ventilating passages may be arranged for at the juncture of the globe 83 with the member 84, and at the juncture of the globe 83 with the hood 82.

The lamp shown and described in detail is intended for operation on a constant current circuit. The various circuits of the lamp, which are shown in the diagram in Fig. 4, are as follows: A conductor 88 extending from a binding post 87, carried by the member 6 and forming one terminal of the lamp, is connected at the point 88' to one terminal of the two coils 28, which are in series with each other. An electrical connection between the point 88' and the electrode 40 is indicated in the diagram by the line 89. In the lamp as actually built a flexible conductor 89' ex-

tends from the point 88' to the arm or bracket 41 carried at the upper end of the tube 38 which is in fixed metallic connection with the electrode 40 through the arm and socket at its lower end. A conductor 90 connects a binding post 86, also carried by the member 6 and forming the other terminal of the lamp, with one terminal of coil 60. The other terminal of coil 60 is connected to one of the screws 15 by a conductor 91. An electrical connection between the screw 15 and the electrode 21 indicated in the diagram by the conductor 92 is actually established by the engagement of the tube 12 with the screw 15 and with the bowed members 22 which support the electrode 21. In addition to the pivotal connection between the bowed members 22 and the tube 12, a flexible conductor 93, having one end clamped to the tube and the other end clamped to one of the members 22, may be employed if desired, as shown in Figs. 1 and 2. One terminal of the resistance conductor 69 is connected to the conductor 90 intermediate its ends at the point 94. A conductor 95 connects the other terminal of the resistance coil at the point 96 with the terminal or contact member 66. Another conductor 97 leading from the point 96 connects the last-mentioned terminal of the resistance 69 and one terminal of the coil 70. The other terminal of the coil 70 is connected by a conductor 99 to one of the terminals of the coils 28 at the point 98. A conductor 100 leads from the point 98 to the contact or terminal member 65. A conductor 101 connects the contact member 75 to the line 90 at 101'. A conductor 102 connects the contact member 76 to the screw 15.

The electrodes 21 and 40 are in the position shown in Fig. 1 when the lamp is out of circuit. Under these circumstances the armature 26 will be down, the contacts 75 and 76 will be separated and the contacts 65 and 66 will be held together by the spring 62'. When the proper circuit connections are made with terminals 86 and 87, current will flow through the windings of the coils 28 causing the armature 26 to be lifted. The upward movement of the armature 26 will carry with it the tube 38 and electrode 40 through the instrumentality of clutch 45. At the same time the electrode 21 will be oscillated about its support by the bar 25. The upward movement of the tube 38, and thereby the movement of the armature 26, will be checked by the engagement of the electrode 40 against the under surface of the arc-shaped electrode 21. The position of the parts at the instant of contact between the electrodes 40 and 21 is shown in Fig. 2. Upon the engagement between the electrodes 40 and 21 current will flow between the terminals 86 and 87 through the conductor 90, coil 60, conductor 91, screw 15, conductor 92, electrodes 21 and 40, and conductors 89 and 88. This current

will energize the electromagnet 60 which will then attract its armature, thus causing a separation of the contacts 65 and 66 and a de-energization of the magnet coils 28, where-
 5 upon the armature 26 will return to its initial position. The return movement of the armature 26 will be considerably slower than its upward movement, owing to the action of its regulating dash pot 31. When the yoke
 10 member of the clutch 45 strikes against the stop 54 the engagement between the clutch and the tube 38 is broken. The downward movement of the tube 38 and electrode 40 will be limited, however, by the engagement
 15 of the pawl 51 with the collar 56. During the initial upward movement of the tube 38 the clutch 45 will travel up with it by reason of their engagement maintained by the spring 52. If the movement of the tube 38
 20 is great enough, however, the pawl will strike against the lug 55 carried on the lower side of the stop 54 which will cause the release of the tube 38 from its engagement with the clutch. When, however, the tube 38
 25 starts downward again the clutch will immediately engage it and will travel down with it until the pawl strikes against the collar. It will thus be seen that the downward move-
 ment of the tube 38 and the electrode 40
 30 taking place when the magnet coils 28 are de-energized will always be limited to the amount of the movement which the pawl can have between the stop 54 and the collar. This in the normal operation of the lamp with
 35 any given adjustment of the stop 54 and the collar will insure an arc of a predetermined length. As long as sufficient current flows through the coil 60 the contacts 65 and 66 will be separated and the current flowing
 40 through the coil 28 will be insufficient to attract the armature 26. In addition to the current flowing in the circuit which includes the electrodes, current will also flow between the terminals 86 and 87 through the circuit
 45 which includes the resistance coil 69, the magnet coil 70, and the magnets 28. The magnet coil 70 is a fine wire coil through which but a comparatively small amount of current is intended to flow. As far as this
 50 circuit is concerned the resistance 69 and the magnet coils 28 simply act as resistances to keep down the current flow in the circuit. The current flowing through the windings of coil 70 will vary with the voltage of the arc.
 55 As the electrode 40 is consumed, the distance between its tip and the electrode 21 will increase. As the current remains constant, the voltage of the arc must increase. In conse-
 60 quence of the increase in voltage of the arc, more current will flow through the windings of the coil 70. The magnet coil 70 is de-
 signed to attract its armature upon a certain predetermined increase in voltage of the arc occurring when the arc increases in length a
 65 certain amount. When the armature 72 is attracted the contacts 75 and 76 will engage and a low resistance shunt, including the line 101, contacts 75 and 76, and line 102, will be closed about the electromagnet 60. As soon as this happens the arm 61 of the electromagnet will be released and the contacts 65 and 66 will be closed by the spring 62'. When the contacts 65 and 66 engage an operative current will flow through the windings of the coils 28 in the manner hereinbefore described. This will cause the armature 26 to be raised until the free end of the electrode 40 engages the under surface of the electrode 21. In this operation the tube 38 will be pulled through the yoke of the clutch 45 a distance
 7 equal to the difference between the entire upward movement of the tube 38 (equal to the length of the arc at the moment at which the movement takes place), and the play of the pawl 51 between the collar 56 and the stop 55.
 8 When the electrode 40 impinges against the under side of the electrode 21, current will begin to flow between the electrodes through the coil 60, causing a separation of the contacts 65 and 66 and consequent de-energization of the magnet coils 28, and dropping of the lower electrode in the manner hereinbefore described.
 9 It will be noted that by reason of the oscillation of the electrode 21 the electrode 40
 95 impinges against, and the arc starts from, a different portion of the electrode 21 from that from which the arc extends during the normal operation of the lamp. This is an important feature, as with many of the elec-
 100 trodes which we employ more or less solid matter is deposited upon that portion of the electrode from which the arc extends in the normal operation of the lamp. The material deposited from such electrodes is usually
 105 more or less non-conducting, particularly when cold. In some cases the conductivity of the electrode 40 is quite low when the electrode is cold. The construction employed insures a contact between electrode 40 and
 110 a clean and hence good conducting portion of the copper electrode 21, both at the initial starting of the lamp and whenever it feeds.
 By arranging the parts so that the walls of the apertures 19 and 20 more or less closely
 115 embrace the electrode 21, or by providing auxiliary scraping means, such as is formed by the apertured plate 103 secured to the member 12 by screws 104 (see Figs. 5 and 6), the oscillatory movement of the electrode 21 taking place whenever the magnets 28 are energized and de-energized, causes the electrode to clean itself.
 The tube sections or chimney members 3,
 8 and 12 form a comparatively long chimney
 125 or draft tube. This chimney forms the back-bone of the lamp, all of the mechanism of the lamp being carried by or from it. The electrode 21 being located at the lower end of the chimney, and the arc being substan-
 130

tially in line with the axis of the chimney, a very considerable draft is produced, which sucks the major portion of the products of combustion of the electrode 40 up the chimney and discharges them through the orifices 4 formed for the purpose in the boss 2. The amount of air necessary to give a proper electrode consumption, and to properly dilute the products of combustion in order to obtain the requisite draft, is admitted through one or more of the following spaces, the opening 85, space between the globe 83 and member 84, and space between the globe 83 and hood 82. By varying the size of these apertures the amount of air admitted can of course be regulated. The action of the draft is highly important on account of its steadyng and centralizing action upon the arc. The construction employed gives the maximum amount of draft possible with a lamp of given dimensions. The outer portion of the member 1 serves as a hood or shade to prevent dust and moisture from entering the chimney through the orifices 4.

While the lamp which we have illustrated and described in detail is particularly adapted for use in a constant current circuit, it will readily be understood that only such changes will be required to adapt the lamp for use on a constant potential circuit as can easily be made by one skilled in the art.

What we claim as new and desire to secure by Letters Patent of the United States, is,

35 1. In an arc lamp, a pivoted non-consuming electrode and a second electrode, and means for simultaneously reciprocating said second electrode and oscillating the non-consuming electrode.

40 2. In an arc lamp, a pair of electrodes; a coil in shunt to the arc for moving them together, a coil in series with the arc for de-energizing the first-mentioned coil, and another coil in shunt to the arc for deenergizing the series coil.

45 3. In an arc lamp, a central draft tube having notches or grooves formed in its lower end, and a movable electrode adapted to pass through said notches or grooves.

50 4. In an arc lamp, a pair of electrodes, means for moving one of said electrodes in a direction to lessen the distance between said electrodes, and means for automatically moving the other of said electrodes back and forth in a direction which maintains the distance between said electrodes at each feeding operation of the lamp.

55 5. In an arc lamp, an electrode, a second electrode having a portion from which the arc is started, and another portion from which the arc is maintained, and a means for moving said latter electrode at each feeding operation to cause the arc to be started between the first portion and the other elec-

trode and to be maintained between the second portion and the other electrode.

6. In an arc lamp, a non-consuming positive electrode, and means for causing an arc to start from one portion of said non-consuming electrode and to be maintained from another portion of said electrode.

7. In an arc lamp, an electrode-carrying rod, a clutch member coöperating therewith, means for moving said clutch member and thereby the rod upward against the action of gravity in order to feed the electrode, a second clutch member coöperating with said rod, stops limiting the movement of said second clutch member, and means for holding said second clutch member in engagement with the rod at all times except when said second clutch member is in engagement with the stop member against which it is moved by the movement of the rod produced by said actuating clutch, the other of said stops limiting the movement in the arc-striking direction of the clutch and thereby the rod.

8. In an arc lamp, a consuming negative electrode, a non-consuming positive electrode, and means for causing an arc between said electrodes to extend from one part of the non-consuming electrode at starting and from another part of said electrode after starting.

9. In an arc lamp, a feeding magnet, a winding in series with the arc for rendering the feed magnet inoperative, and a winding in shunt to the arc for rendering the series coil inoperative whenever the voltage of the arc exceeds a predetermined amount.

10. In an arc lamp, the combination of a draft tube having diametrically opposite slots, an electrode mounted on the draft tube, and means for moving the electrode through and in scraping engagement with the walls of the slots.

11. In an arc lamp, an electrode carrying member, a clutch actuated to engage said member and to move it in one direction, a second clutch actuated to release said member for gravitational movement in the other direction and means coöperating with the first-named clutch to arrest the member after gravitational movement through a predetermined distance.

115 12. In an arc lamp, an electrode-carrying member, an actuating clutch therefor, means for moving said actuating clutch and thereby the member in one direction, said clutch member being allowed to return to the starting position under the influence of gravity, and said clutch being arranged to disengage the member on such return, a second clutch playing between a pair of stops, and means tending to hold said second clutch always in engagement with said member except when it engages one of the stops between which it plays.

13. In an arc lamp, an electrode-carrying member, an actuating clutch therefor, means for moving said clutch to cause it to engage said member and move it in one direction, 5 and a second clutch normally engaging said member and playing between stops, the distance between said stops being less than the normal movement of the actuating clutch.
14. In an arc lamp, an electrode-carrying member tending to move by gravity to establish the arc and an arc length limiting clutch coöperating therewith, fixed stops between which said clutch moves, and means independent of the member for holding said 15 clutch member in engagement with the electrode-carrying member at all times except when the movement of said clutch member is checked by its engagement with one of said stops.
15. In an arc lamp, a draft tube, a consuming electrode located in line with the axis of said tube, a non-consuming electrode located at the lower end of said tube, and means for moving it transversely of said 20 tube in the feeding operation of the lamp.
16. In an arc lamp, a platform, an arc inclosing globe below said platform, a casing above said platform, electrode feeding mechanism located within said casing, a draft 25 tube projecting through said platform with its lower end terminating just above the normal position of the arc in said arc inclosing globe and its upper end projecting through said casing, said draft tube forming 30 the backbone of the lamp.
17. In an arc lamp, a movable electrode, a clutch for moving said electrode in one direction, a second clutch for releasing the electrode for movement in the opposite direction and a stop for limiting the movement to a predetermined distance, and means for actuating the clutches. 35
18. In an arc lamp, a chimney, an electrode, and means for moving the electrode about a fixed axis transversely within and through the chimney. 40
19. In an arc lamp, a negative consuming electrode movable in the direction of its length, and a positive non-consuming electrode which oscillates transversely with respect to the line of movement of the negative electrode. 45
20. In an arc lamp, a negative consuming electrode movable in the direction of its 50 length, a positive non-consuming electrode 55 movable transversely to the line of movement of the negative electrode, and means for automatically moving said electrodes in the manner described to start an arc between the negative electrode and one portion of the positive electrode, and to cause said arc to be normally maintained between the negative electrode and a second portion of said positive electrode.
21. In an arc lamp, a draft tube or chimney having an aperture formed in it, an electrode in the form of an arc shaped bar pivotally connected to the draft tube or chimney number and passing through said aperture, and a feeding mechanism for 60 starting and drawing an arc from said electrode, said feeding mechanism comprising means for causing the normal arcing portion of the electrode to be moved out of and back into said draft tube or chimney member at 65 each feeding operation.
22. In an arc lamp, a negative electrode movable in the direction of its length, a positive electrode the arcing surface of which is movable transversely to the line of movement of the negative electrode, a device for 70 cleaning the arcing surface of the positive electrode, and a feeding mechanism for moving the negative electrode in the direction of its length and for moving the positive 75 electrode so that its arcing surface is brought into contact with the cleaning device at each feeding operation.
23. In an arc lamp, a negative electrode movable in the direction of its length, a positive non-consuming electrode, a cleaning device, a feeding mechanism for bringing about an engagement between the electrodes to start an arc, said feeding mechanism comprising means for producing a relative movement between the positive electrode and the cleaning device at each feeding operation whereby the portion of the positive electrode from which an arc normally extends is cleaned at each feeding operation 100 of the lamp.

In witness whereof, we have hereunto set our hands this twelfth day of November, 1903,

RICHARD FLEMING.
